MECHANICAL PENCIL

Anton T. Otto and Victor A. Strom,
Alameda, Calif.

Application July 28, 1941, Serial No. 494,303

7 Claims. (Cl. 120—18)

This invention relates to improvements in mechanical pencils and more particularly to the crayon guiding means thereof.

Among the objects of the invention is the provision of means to prevent the fouling of the feed mechanism by abrasions from the crayon.

Another object is to hold the crayon within the pencil without exerting constrictive pressure against it.

Another object is to facilitate the reloading of the pencil.

Another object is to reinforce the crayon against warping and breakage before it is loaded into the feed mechanism.

A further object is to encase the crayon in a nonabrasive, nonabsorbent sheath that will protect it against the deleterious effect of atmospheric temperature.

Other objects and advantages will appear as the description progresses.

Crayons for marking on glass, porcelain, metal and similar smooth and nonabsorbent surfaces are composed of waxlike and highly adhesive materials. Such compositions have a strong affinity for the metals, plastics or other materials entering into the structures of mechanical pencils, in which the crayon is pushed outward from the holder. Because of its essentially adhesive nature the sides of the crayon are abraded by the contacting tubular portion of the prior types of holders. Such abrasion builds up on the walls of the guiding nipple to such an extent that the bore of the nipple becomes too small to receive or feed the reloads of crayon. Such abrasions interfere with the smooth feeding of the crayon as desired for marking purposes. These disadvantages are overcome by the use of the present invention.

Broadly stated the invention consists in encasing the crayon in an inexpensive sheath having a low coefficient of friction, such as waxed paper, but with sufficient adhesive lubricating qualities to hold the crayon therein without abrasion.

In this specification and the accompanying drawing the invention is disclosed in its preferred form. But it is to be understood that it is not limited to this form because it may be embodied in modifications within the spirit of the invention as defined in the claims following the description.

In the one sheet of drawings:

Fig. 1 is a side elevation of a mechanical pencil, partially in longitudinal section embodying this invention.

Fig. 2 is an enlarged detail in longitudinal section of the crayon holding end of the same con-

structed and combined in accordance with this invention.

Fig. 3 is an end view of the crayon enclosing sheath.

In detail the construction illustrated in the drawing, referring first to Fig. 1, comprises the tapered finger grip portion 1, having the integral tubular reduced diameter stem 2, center bored throughout its length. The finger grip portion 1, is counterbored as at 3, and has the internal thread 4 adjacent its outer end. Throughout its length the stem 2 has the slot 5 extending outward from the center bore.

The plunger 6 slides freely in this centerbore 13 and has two interspaced transverse holes therethrough near its rear end. The wire helix 7 encircles the stem 2 and is freely slidable thereon and has its opposite ends 8, 9, bent inwardly through the slot 5 to engage the holes in the end 20 of the plunger 6.

The sleeve 10 encircling the stem 2, rotates freely thereon and is internally threaded to engage the helix 7. Rotation of the sleeve acting through the helix 7 advances or retracts the plunger 6 within the stem.

The head 11 has its inner end bored to snugly fit the end of the stem 2 protruding beyond the sleeve. The screw 12 extends through the wall of the head 11 and the stem 2 and is threaded in the plug 13 which snugly fits the bore in the stem. By this means the plug acts with the head of the screw to clamp the head 11 securely onto the end of the stem 2. In practice the screw 12, extends through the slot 5 to engage the plug 13; but for convenience in illustration it is otherwise shown in Fig. 1.

This screw 12 also passes through the band of the pocket clip 14 encircling the head 11 and having the ball end 15 resiliently bearing against the periphery of the sleeve 10. The outer end of the head 11 can be bored to act as a receptacle for spare crayons, and is closed by the polygonal cap 16 screwed therein. The specific structure and mode of operation described is not essential to the functioning of the present invention, since it is applicable to the many types of mechanical pencils available and adapted to the extension of the crayon for the purpose intended.

The finger grip portion 1, illustrated in enlarged detail in Fig. 2, is provided with the nipple 17, having its outer end tapered toward the end of the crayon 18. Intermediate its length it is externally threaded at 19 to engage the internal threads at 4. It has the extension 20 of reduced diameter to leave the annular space 21 within the

counterbore 3. The end of this extension alines with the shoulder 22 forming the bottom of the counterbore, toward which it can be advanced by the threads 4-19. This nipple has a center bore slightly greater than the diameter of the crayon. This difference in diameters leaves clearance for the thickness of the sheath 23 enclosing the crayon 18, and snugly fitting within the centerbore of the nipple 17. The inner end of this sheath is slit to form the tabs such as 24, see Fig. 3, extending beyond the end of the crayon.

To insert the sheathed crayon 18, remove the nipple and insert the sheath 23 therein from the rear, leaving the tabs 24 extended beyond the end of the nipple. Then push the extension 20 into the front end of the finger grip portion; this will fold the tabs 24 backward against the outer diameter of the extension 20. Screwing the nipple into place clamps the tabs 24 firmly between the shoulder 22 and the inner end of the extension 20. Preferably the crayon is inserted in the sheath before it is placed in the nipple. Thus assembled the crayon 18 is alined with the plunger 6 and is fed outward by the movement of the plunger actuated by revolving the sleeve 10, to advance the helix 7.

After the plunger has been advanced to the limit to eject the remnant of the used crayon, the plunger is retracted and a new sheathed crayon is inserted in the nipple by the method described. Each sheath will outlast many crayons, which makes reloading the simple matter of inserting the new unsheathed crayon without removing the nipple 17 from the holder, if preferred. When the sheath becomes worn the nipple 17 is unscrewed and a new sheath inserted as described.

If desired the end 6' of the plunger 6 may be made concave to scrape the inner bore of the sleeve free from any unevenness or abrasions from the crayon, which may occur due to oversize or uneven crayons. It has the further advantage that it will not mushroom the head of the crayon when softened by heat.

The sheath 23 is preferably formed of helically wound paper tubing, such as drinking "straws," heavily impregnated with hot paraffin or other waxlike liquids. When properly set this impregnating material presents a lubricated surface to the advancing crayon without any abrasive effect against it. Yet such a surface presents sufficient adhesiveness to prevent the movement of the crayon within the sheath, except by the force of the plunger 6. It is also sufficiently adhesive to prevent the crayon turning within the sheath during the act of marking with the crayon. The cushioning effect of the fibrous flexible sheath interposed between the crayon and the end of the metallic nipple minimizes scoring and breakage of the crayon at this point under the lateral pressure of marking.

If the sheath 23 is long enough to project a short distance from the end of the nipple 17, as in Fig. 2, it prevents the metal nipple 17 from scratching the surface being marked. This is an advantage in marking aluminum parts of airplanes and other easily scratched surfaces requiring the use of such crayons.

Having thus described this invention what is claimed and desired to secure by Letters Patent is:

1. A crayon surrounded by a sheath of impregnated material, for use in mechanical pencils adapted to hold said sheath against movement relative to said crayon, while advancing said crayon.
2. A mechanical pencil including a tubular sheath lined with a wax-like lubricant and adapted to guide a crayon therein; and means for advancing the crayon through said sheath.
3. A mechanical pencil including a nipple adapted to guide a crayon therein; means for advancing the crayon through said nipple; and a sheath interposed between said nipple and crayon and having lubricating qualities with respect to said crayon.
4. A mechanical pencil including a nipple adapted to guide a crayon therein; means for advancing the crayon through said nipple; and an impregnated sheath fixed in said nipple between said nipple and crayon.
5. A mechanical pencil including a counterbored finger grip portion having a crayon guiding nipple therein; an impregnated sheath within said nipple and having one of its ends clamped between the end of said nipple and an abutment on said finger grip portion; and means for advancing a crayon through said sheath.
6. A mechanical pencil including a counterbored finger grip portion; a crayon guiding nipple threaded in said portion and having a reduced diameter extension with its end engageable with an abutment in said counterbore; a sheath of flexible material within said nipple and having its inner end clamped between the end of said extension and said abutment; and means for advancing said crayon through said sheath.
7. A mechanical pencil including a counterbored finger grip portion; a crayon guiding nipple threaded in said portion and having a reduced diameter extension with its end engageable with an abutment in said counterbore; a tubular sheath of flexible material within said nipple and having tabs on its inner end folded back over said extension within said counterbore; and means for advancing a crayon through said sheath.
